PICK-UP AND WINDROWING DEVICE

Wilfred A. Blaser and Roy W. McLain, Davenport, Iowa, assignors to Innes Company, Bettendorf, Iowa, a corporation of Delaware

Application May 4, 1953, Serial No. 352,848

8 Claims. (Cl. 56—370)

This invention relates to a pick-up and windrowing device for harvesting beans, peanuts, and similar vegetation. In such a harvest field, it is very desirable to be able to pick up the already cut or pulled up vines and deposit them in windrows, and this machine furnishes an improved means for that purpose.

Among the objects of this invention are the provision of an improved machine for gathering crops into windrows; the provision of means for separating dirt and stones from vegetation; the provision of means which will render it impossible to accidentally separate a cross-conveyor from a pick-up unit; the provision of means to render more easily and readily the attachment and detachment of a cross-conveyor unit; the provision of means for driving an apron of a pick-up and, simultaneously, driving the apron of a cross-conveyor; and such further objects, advantages, and capabilities as will hereafter appear and as are inherent in the construction disclosed herein.

Our invention further resides in the combination, construction, and arrangement of parts illustrated in the accompanying drawings and, while we have shown therein what is now regarded as the preferred embodiment of this invention, we desire the same to be understood as illustrative only and not to be interpreted in a limiting sense.

In the drawings annexed hereto and forming a part 40 hereof,

Fig. 1 shows a perspective view of a pick-up mechanism forming a part of the present invention;

Fig. 2 shows a perspective view of a cross-conveyor and part of the pick-up of the present invention;

Fig. 3 shows a plan view of the present invention;

Fig. 4 shows an end view of the structure shown in Fig. 3;

Fig. 5 shows a fragmentary rear view of the structure shown in Fig. 2;

Fig. 6 shows a cross-section through the rollers in Fig. 7;

Fig. 7 shows a plan view of the right hand end of the pick-up in the direction of the arrows 7—7 in Fig. 6;

Fig. 8 shows a fragmentary plan view of the rear part of the pick-up with a portion of the cross-conveyor, along the plane indicated by the line 8—8 in Fig. 6;

Fig. 9 shows a cross-section of the structure shown in Figure 8, along the plane indicated by the line 9—9 in that figure; and

Fig. 10 shows a plan view of the left hand end of the structure shown in Fig. 7, Figs. 7 and 10 showing the right and left ends, respectively, of the structure shown in Fig. 5.

In the mobile pick-up unit P, best shown in Fig. 1, the crops are picked up in the customary manner by pick-up mechanism in the form of a drum or cylinder 1 provided with protruding and withdrawable fingers 2, as is well known. These crops are delivered to a draper or apron 3 and carried upwardly and rearwardly to a cross-conveyor 5, when such is used. This cross-conveyor is detachable and can be used or not as conditions require.

2

When not used, a single windrow of vegetation results; when used, it serves to unite the windrow with one or more previously laid, resulting in a multiple windrow.

In this vegetation handling machine, it is necessary to get the crop to the cross-conveyor and, therefore, the draper or apron 3 is placed above and to the rear of the pick-up drum 1 so that the crop will be elevated and dropped on the draper 4 of the cross conveyor 5, to be carried toward the right of Fig. 2. In this figure, a roller 6, at the end of the draper 4, is spaced from the end of the draper and is provided with ridges to form a species of slinger which carries the crop over past the roller 6 and forms a windrow. A space 8 (Figs. 8 and 9) is left between the roller 6 and a roller 9, forming a part of the cross-conveyor. This space 8 allows stones and dirt, picked up, to be dropped on the way to the roller 6, but the crop is not also dropped through this space but is delivered in a windrow at the end of the cross-conveyor.

This cross-conveyor unit has another roller 10 at the left end thereof, as shown in Fig. 4. This cross-conveyor has an upstanding rear frame in the form of a wind shield 11 to prevent vegetation from being thrown off the rear of the conveyor platform. Metal braces 12 and 13 are placed longitudinally of the shield, and a support 14 rises from these braces 12 and 13 and journals the rear part of a telescopic shaft assembly 15.

At one end of the shield 11 is a stiffening member 18 which serves to stay or support the shield. A rod or link 19 is connected to this stiffening member 18 and is also detachably connected to a bracket 20 rising from a transverse, upper horizontal member 33 forming a part of the main frame of the pick-up unit. A second stiffening member 22 also rises from the metal braces 12 and 13 and helps hold the shield 11 in place. A rod or link 23 is connected to the end of the stiffening member 22, the second end of the rod 23 being detachably connected to one end of a bracket 35 on the horizontal member 33. These links serve as detachable connecting means between the units.

Another rod 24 is secured to a bracket 25 on the top of the shield 11 and is secured detachably to a storage means in the form of a clip 26 on the tubular frame member 33. From this position, the rod 24 may be detached and connected to a bracket 27 on a lever 28 to afford lifting and lowering means for the cross-conveyor unit 5. A horizontal shaft 21 has crank arms 29 extending therefrom, and from these crank arms 29 extend flexible means or chains 30 which are connected at their other ends to drum-supporting end plates 31 to vertically adjust the pick-up drum.

The horizontal shaft 21, as shown in Fig. 1, extends through sector 32, which is secured to the tubular frame member 33. Laterally spaced apart, generally upright frame members 34 are secured to and depend from the cross member 33 and are in turn rigidly cross-connected by a transverse lower main support or bar 33a the members and bar thus affording a pick-up unit main frame which is supported on and rises from ground wheels 47, which wheels are journaled on suitable bracket and axle assemblies 47a. A drive shaft 36 is connected to the power take-off of the tractor (not shown) and passes through bearings 37 on the tubular frame member 33. This drive shaft 36 drives a sheave 38 and is connected to the front part of the shaft assembly 15. A belt 41 passes over a sheave 39 on the rear of the shaft assembly 15 and passes also over a sheave 40 to drive the draper 4. The sheave 38 drives a belt 42 and, with this, a sheave 43 which drives a shaft 44. This shaft 44 drives a roller 45 and the apron or draper 3. A chain drive 46 causes the roller 6 to be driven.

The shaft 44 serves also as a transverse pivot for the end plates 31, between which the pick-up drum 1 is

jounaled. Hence the adjusting means afforded by the lever 28 operates through the rockshaft 21, arms 29 and chains 30 to adjust the height of the drum 1.

Plates or ears 48, welded to the pick-up unit lower frame member 35, are spaced slightly apart and have holes therethrough to receive a pivot member or rod 49 to form part of a hanger or hanging means for supporting the cross-conveyor unit 5 which has a front transverse frame member 5a including hooks 50 to be hooked on the rod 49, the hooks comprising further parts of the hanger means and affording a separable pivotal connection between the pick-up and cross-conveyor units. When the cross-conveyor unit 5 is hung on these hangers and the back of the conveyor is raised, the hooks cannot be lifted from the rod 49, because of the angle of the cross member 33a (Fig. 6) which makes it impossible for the cross-conveyor to bounce off of the hangers during normal operation.

When the cross-conveyor 5 is detached from the pick-up unit, the rods 19 and 23 are detached from the brackets 20 and 35, respectively, and the rod 24 is detached from both the clip 26 or bracket 27. The hooks 50 are disengaged from the rods 49. To attach the cross-conveyor 5, the hooks 50 are engaged in the rods 49, the handle 28 is raised to the highest notch in sector 32, and the loose end of rod 24 is attached to bracket 27. Handle 28 is then lowered, lifting the cross-conveyor 5 to its required height, at which point the rods 19 and 23 are attached in their operative positions to the brackets 20 and 35, respectively. Then the forward end of the rod 24 is moved from the bracket 27 to the clip 26, where it remains during the operation of the machine, leaving the handle 28 to be used solely for raising and lowering the pick-up. Hence, the handle 28 serves a dual purpose, that of raising and lowering the pick-up and that of assisting in attaching and detaching the cross-conveyor.

Mechanisms 51 and 52 permit the operator to adjust the tension of the draper 4 by adjusting the position of the roller 10. The direction of travel of the drapers is shown by the arrows in Fig. 3.

The tongue 54, rigidly attached to the pick-up unit frame 33, 34, 33a has a plate 58 swingably attached to it by means of the transverse shaft 57. The plate 58 is attached to the traction unit. If a single bolt is used in hole 55, the plate 58 becomes swingable about a vertical axis and the windrower will trail, but if bolts are used in both holes 55 and 56, the plate 58 becomes rigid and will not trail. However, the windrower is then swingable vertically about the transverse shaft 57 and can therefore be lifted about shaft 57 by suitably connecting the frame member 33 of the windrower to the lifting means which is normally built into the traction unit. In either event, the pick-up unit is supported in part by its tongue 54 on a tractor and in part by its wheels 47 and the drum 1 is adjustable vertically relative to the frame 33, 34, 33a as already described.

This machine has the pick-up drum of well known characteristics which picks up cut vegetation and delivers it to the apron 3 which drops the vegetation on the draper or cross-conveyor 4 which is normally run to the right, as viewed in Fig. 3. The roller 6 at the end of the cross-conveyor 4 carries the vegetation to the right and drops it in a windrow. By a proper arrangement of the swaths of the pick-up, two, four, six, or eight rows of beans, peanuts, or other vegetation can be collected into one windrow.

It is of course understood that the specific description of structure set forth above may be departed from without departing from the spirit of this invention as disclosed in this specification and as defined by the appended claims.

Having now described our invention, we claim:

1. A harvester of the class described, comprising: a mobile pick-up unit adapted to advance over a field and including ground wheels, a pick-up unit main frame sup-

ported by and rising from the ground wheels and having upper and lower frame members transverse to the line of advance, pick-up mechanism ahead of and connected to the main frame for vertical adjustment relative to said frame, and an adjusting lever movably mounted on the upper frame member and connected to and for adjusting the pick-up mechanism; a cross-conveyor unit disposed behind the pick-up unit main frame and extending transversely of the line of advance, said cross-conveyor unit having a front transverse frame member adjacent to the lower frame member of the pick-up unit main frame and further having a rear frame spaced rearwardly from and rising generally to the level of the upper frame member of the pick-up unit main frame; hanger means detachably interconnecting the units, including a separable pivotal connection between the lower pick-up unit frame member and the cross-conveyor front frame member, said pivotal connection affording a pivot on a transverse axis about which the cross-conveyor unit may be raised and lowered relative to the pick-up unit and said pivotal connection further including cooperative separable parts respectively on said units enabling upward and rearward separation of the cross-conveyor unit when lowered; a lifting and lowering link carried by the cross-conveyor unit rear frame and detachably connectible to the pick-up unit adjusting lever so that movement of the lever selectively in opposite directions respectively lifts and lowers the cross-conveyor unit about said pivot axis; and detachable means connectible between the units for supporting the cross-conveyor unit in lifted position when the lifting and lowering link is detached from said lever.

2. The invention defined in claim 1, including: means on the pick-up unit frame for receiving the lifting and lowering link when said link is detached from the lever.

3. The invention defined in claim 1, in which: the cooperative parts of the separable pivotal connection are so constructed and arranged as to prevent upward and rearward separation of the cross-conveyor unit while said cross-conveyor unit is in its lifted position.

4. A harvester of the class described, comprising: a mobile pick-up unit adapted to advance over a field and including ground wheels, a pick-up unit main frame supported by the ground wheels, pick-up mechanism connected to the main frame for vertical adjustment relative to said frame, and adjusting means movably mounted on said frame and connected to and for adjusting the pick-up mechanism; a cross-conveyor unit disposed behind the pick-up unit main frame and extending transversely of the line of advance, said cross-conveyor unit having a front transverse frame member adjacent to the pick-up unit main frame; hanger means detachably interconnecting the units, including a separable pivotal connection between the pick-up unit frame and the cross-conveyor front frame member, said pivotal connection affording a pivot on a transverse axis about which the cross-conveyor unit may be raised and lowered relative to the pick-up unit and said pivotal connection further including cooperative separable parts respectively on said units enabling separation of the cross-conveyor unit when lowered; lifting and lowering means carried by the cross-conveyor unit rearwardly of said front frame member and detachably connectible to the pick-up unit adjusting means so that movement of the adjusting means selectively in opposite directions respectively lifts and lowers the cross-conveyor unit about said pivot axis; and detachable means connectible between the units for supporting the cross-conveyor unit in lifted position when the lifting and lowering means is detached from said adjusting means.

5. The invention defined in claim 4, including: means on the pick-up unit frame for receiving the lifting and lowering means when said means is detached from the adjusting means.

6. The invention defined in claim 4, in which: the cooperative parts of the separable pivotal connection are so constructed and arranged as to prevent upward and

75

rearward separation of the cross-conveyor unit while said cross-conveyor unit is in its lifted position.

7. A harvester of the class described, comprising: a mobile pick-up unit adapted to advance over a field and including ground wheels, a pick-up unit main frame supported by and rising from the ground wheels and having a rear frame member transverse to the line of advance and spaced above the ground, and pick-up mechanism ahead of said rear frame member; a generally rectangular cross-conveyor having its length transverse to the line of advance and behind the pick-up unit and selectively mountable on and demountable from the pick-up unit, said cross-conveyor unit having a transverse front frame member and positionable in a demounted position lying on the ground with said front frame member below the level of the pick-up unit rear frame member or in a mounted position clear of the ground and with said front frame member substantially at the level of said rear frame member; hanger means for detachably supporting the front frame member on the rear frame member when the front part of the cross-conveyor unit is lifted to mounted position with the cross-conveyor unit inclining downwardly and rearwardly from said hanger means, and said hanger means including a pivot on a transverse axis; means cooperative between the units for exerting a lifting force on the cross-conveyor unit to swing said unit upwardly about said axis to complete the mounted position thereof; and means detachably securing said cross-conveyor unit to the pick-up unit in said mounted position.

8. A harvester of the class described, comprising: a mobile pick-up unit adapted to advance over a field and including ground wheels, a pick-up unit main frame supported by and rising from the ground wheels and having a rear frame member transverse to the line of advance and spaced above the ground, and pick-up mechanism

10

15
